UNITED STATES PATENT OFFICE.

ELBERT J. CLARK, OF WINNEBAGO, ILLINOIS.

PAPER-CUTTING MACHINE.

SPECIFICATION forming part of Letters Patent No. 261,676, dated July 25, 1882.

Application filed April 7, 1882. (No model.)

To all whom it may concern:

Be it known that I, ELBERT J. CLARK, of Winnebago, in the county of Winnebago and State of Illinois, have invented certain new 5 and useful Improvements in Paper-Cutting Machines; and I do hereby declare that the following is a full, clear, and exact description of the invention, which will enable others skilled in the art to which it appertains to make and 10 use the same, reference being had to the accompanying drawings, which form a part of this specification, and in which—

Figure 1 is a plan or top view of the machine. Fig. 2 is a transverse section of the same 15 through the knife or cutter and presser-bar, as indicated by the broken line marked *xx* in Fig. 1. Fig. 3 is a similar section through the bed-plate, with its presser-bar and one of the tightening-screws, as indicated by the broken 20 line marked *yy* in Fig. 1; and Fig. 4 is a perspective view of the knife or cutter.

Similar letters of reference indicate corresponding parts in all the figures.

My invention has relation to machines or 25 apparatus for cutting or trimming paper, books, magazines, &c.; and it consists in the construction of a simple and inexpensive apparatus of that class which is particularly adapted for office and family use, or for the use of physicians and druggists to cut up paper for packing or wrapping powders and other medicines.

In the accompanying drawings, A represents 30 the bed of the machine, which is simply a flat board of suitable size—say about two feet long by fourteen inches wide, more or less—the face of which has parallel lines *a a* half an inch apart, and a corresponding half-inch scale, *b*, marked on one edge. Near the left-hand edge of the bed, about one inch from each end, is 35 bored a hole, *c*, through which works a screw, *D*, having a lever handle or arm, *d*, at its upper end and a nut or button, *e*, at its lower end.

B is the presser-bar, which is of the same 40 length as the bed A, and provided with a longitudinal slot or mortise, *B'*. At each end of the bar are holes *f*, capped with iron nuts *g*, through which the screws *D* work, as shown 45 more clearly in Fig. 3 of the drawings, so that by turning the two screws bar B may be

brought down against the bed or whatever is 50 placed upon it with considerable pressure.

C is the knife or cutter, which has a rounded or oval cutting-edge and a shank, *C'*, which is inserted through the middle of the handle E, to which it is nutted at *h*. The middle part 55 of the handle, through which the knife is inserted, is mortised or recessed to form guides *E' E'* on each side of the knife, which slide upon opposite sides of the presser-bar, the space between the guides being of a width corresponding to the width of the slotted bar B.

In using the machine the paper to be cut is placed upon the bed and gaged by means of the gage-lines *a* and scale *b*, bar B having first been raised to permit the paper to be placed 65 under it. It is then screwed down, the knife is inserted through the vertical slot *B'* in the presser-bar, and by taking hold of both ends of the handle E and drawing it forward and back over the paper this is speedily cut with 70 a smooth and even edge. The bed A is fastened to the edge of the bench or table T, upon which it is placed, by means of an ordinary screw-clamp, F, or other suitable means.

This machine, it will be seen, is exceedingly 75 simple and inexpensive, is always handy and ready for use, and contains no complicated parts liable to break or get out of order.

Having thus described my invention, I claim and desire to secure by Letters Patent of the 80 United States—

The machine or apparatus for cutting and trimming paper herein shown and described, the same consisting of the graduated bed A, having holes *c c*, screws *D D*, slotted presser-bar B, and cutter C, mounted in a handle, E, having parallel guides *E' E'*, the whole constructed and combined substantially in the manner and for the purpose herein shown and set forth.

In testimony that I claim the foregoing as my own I have hereunto affixed my signature in presence of two witnesses.

ELBERT J. CLARK.
